(57) **CLAIM**

The ornamental design for a lid handle, as shown and described.

DESCRIPTION

FIG. 1 is a perspective view showing my new design for a lid handle,

FIG. 2 is a front view thereof,

FIG. 3 is a top view thereof,

FIG. 4 is a cross sectional view of FIG. 3,

FIG. 5 is a perspective view of a second embodiment of the lid handle;

FIG. 6 is a front view thereof,

FIG. 7 is a top view thereof,

FIG. 8 is a cross sectional view of FIG. 7,

FIG. 9 is a perspective view of a third embodiment of the lid handle,

FIG. 10 is a front view thereof,

FIG. 11 is a top view thereof; and,

FIG. 12 is a cross sectional view of FIG. 11.

The arrows in the drawings do not form part of the design, they merely indicate the cross-sections plane; the broken lines in the drawings depict portions of the lid handle that form no part of the claimed design.
